UNITED STATES PATENT OFFICE.

JAMES THORN GOODFELLOW, OF HUNTINGDON, PENNSYLVANIA, ASSIGNEE
TO THE IRON CAR COMPANY, OF CONNECTICUT.

CAR-BODY.

SPECIFICATION forming part of Letters Patent No. 404,535, dated June 4, 1889.

Application filed August 16, 1888. Serial No. 282,836. (No model.)

To all whom it may concern:

Be it known that I, JAMES THORN GOODFELLOW, of Huntingdon, in the county of Huntingdon and State of Pennsylvania, have 5 invented an Improvement in Railroad-Car Bodies; and the following is declared to be a description of the same.

Before my invention railroad-cars adapted for the transportation of lumber and other 10 merchandise of a similar character have not been adapted for carrying coal or grain or merchandise of a similar character, and likewise cars especially constructed for carrying hard and soft coal, coke, ore, grain, &c., have 15 not been adapted for carrying lumber or merchandise, either loose or in boxes or barrels, and the various types of especially-adapted cars having these differing carrying capacities are of almost wholly different construction. 20

My invention relates to a railroad-car body for carrying freight, which car-body is of any well-known form, but preferably of the well-known flat or gondola shape, and which car-body, by its peculiar construction, is adapted 25 equally well for carrying either merchandise—such as lumber or such other merchandise as coke, coal, ore, and similar commodities—which latter merchandise is preferably 30 delivered from the car by means of a hopper or chute beneath the car, or a similar device.

My invention consists in a railroad-car body—such as a flat or gondola car—wherein a portion of the bottom of the car is made as 35 hinged doors, which in one position are secured level with the remainder of the bottom of the car and which in their other position can be dropped by suitable mechanism, so as to form openings in the bottom of the car, and inclines or chutes by which the contents of the car 40 are discharged; and I employ operating-shafts, winding-chains, and a combination of links for raising, lowering, and supporting these hinged doors. This mechanism, including 45 the operating-shaft, is located beneath the bottom of the car and out of the way of any merchandise with which the car may be loaded, and said mechanism is so constructed as to be operated by tools at present in use 50 upon railroads for operating the shafts of car-hopper-discharging doors.

In the drawings, Figure 1 is a longitudinal section of one end of the car-body with the hinged doors closed, and Fig. 2 is a similar view with the hinged doors open. Fig. 3 is 55 a plan of one end of the car-body, half of the car being shown in plan with the floor intact and the other half with the flooring removed. Fig. 4 is a side elevation of one end of the car-body. Fig. 5 is an elevation endwise of 60 the car-body; and Fig. 6 is a cross-section of the car-body at the lines *xx*, Fig. 3.

The car-body shown in the drawings is that of a flat or gondola car, and is made with sides *a*, ends *b*, and a bottom *c*, and these parts are 65 joined together by vertical irons and corner angle-irons in the well-known manner of constructing such cars, and said car is supported or carried by longitudinal side frames composed of tubes *d*, that are connected together 70 and braced or supported in a manner similar to the constructions shown and described in Letters Patent Nos. 308,034 and 385,177, heretofore granted to me, and at *e* there is a draw-bar of any well-known construction, and the 75 running-gear is indicated at *f* by dotted lines. These parts heretofore described form no part of my invention, and do not require a more full description.

My improvement consists in the hinged 80 doors *h*, which are formed in the flat bottom of the car, and the size of which may be varied according to the circumstances of use. The doors *h* are shown as hinged at *i* to rods secured to the bottom of the car, and said doors 85 are located between the angle-iron strips *k* and the T-angle-iron strips *l*, which strips *kl* are let into and fastened to the timbers and frame of the bottom of the car. The manner of hinging the doors may, however, be modified, and there are vertical depending strips or aprons *m m'*, that are fastened to the under side of the bottom of the car, outside of the width of the hinged doors *h*, and these aprons, when the doors are down in the position shown in Fig. 2, form side guides for 95 the material being discharged. The device for supporting and operating the hinged doors consists of the strut-links *n*, tensile-links *o*, and operating-links *r*, and the chains *s*, one 100 end of which is connected to an eye upon the operating-link *r*, and the other end of which

is connected to and wound around the operating-shafts t . These shafts t pass across the car from one side to the other, beneath the bottom c , and upon one end of the shafts t 5 there are ratchets t' and engaging-pawls t^2 , and the ends of said shafts are made square, so that they can be turned by an ordinary operating-wrench.

The strut-links n are connected at their 10 upper ends pivotally to the under side of the hinged doors h , and the tensile links o are connected at one end pivotally to the car-body, and there are short shafts u passing through 15 the lower ends of the links n , o , and r , which shafts form hinged joints for said links, said links being duplicated at each end of the shaft u , at each side of each of the hinged doors. The links r may be replaced by a continuation 20 of the chains s . It is preferable to construct these hinged doors in pairs that open downwardly away from each other, forming a V -chute, delivering in one or more piles the 25 contents of the car, which pass through the openings in the bottom of the car formed by the dropping of the doors.

From the drawings, Fig. 1, it will be seen 30 that the links n , o , and r form a truss, as it were, for the support of the hinged doors, the links r and o being inclined at about an angle of forty-five degrees, while the links n are vertical, or approximately so, and support the 35 weight of the contents of the car that are directly in the doors and part of the weight of the doors, and said doors close up snugly and securely against the surfaces of the angle-iron strips k and l in such a manner as to form, with the balance of the car-bottom c , an even and smooth surface, which is adapted to support and transport lumber or similar merchandise that requires to lie flat upon bottom 40 c , and when the car is required to transport coal, coke, ore, or similar merchandise that requires to be delivered beneath the car the same is equally available, and said materials 45 can be discharged at their point of destina-

tion by the hinged doors h , which can be dropped, as heretofore described.

I claim as my invention—

1. The combination, in a freight-car, with the bottom c , of hinged doors h , connected to 50 and, when closed, forming a portion of the level and even bottom of said car, and with mechanism, substantially as described, for dropping said doors to discharge the contents of the car, and for raising said doors and supporting them in place, substantially as set forth.

2. The combination, in a freight-car, with the bottom c , of the hinged doors h , connected to and, when closed, forming a portion of the 60 bottom of said car, the strut-links n , connected at one end to the hinged doors, the tensile links o , connected at one end to the car-body, the shaft u , to which the other ends of the links n and o are pivoted, and operating-links 65 r , connected at one end to the shafts u , the chains s , and cross-shafts t , by which the hinged doors are supported and operated, substantially as and for the purposes set forth.

3. The combination, in a freight-car, with 70 the bottom c , of the hinged doors h , connected to and, when closed, forming a portion of the bottom of said car, the strut-links n , connected at one end to the hinged doors h , the tensile links o , connected at one end to the car-body, 75 the shaft u , to which the other ends of the links n and o are pivoted, and operating-links r , connected at one end to the shafts u , the chains s , and cross-shafts t , by which the hinged doors are supported and operated, and 80 the angle-iron bars k l , connected to the bottom of the car and at two or more opposite edges of the hinged doors, substantially as and for the purposes set forth.

Signed by me this 1st day of August, 1888.

JAMES THORN GOODFELLOW.
